INVENTOR
CHARLES C. SCHREIL

BY
A. D. T. Libby
ATTORNEY

UNITED STATES PATENT OFFICE.

CHARLES C. SCHREIL, OF CHICAGO, ILLINOIS.

ELECTRICAL SWITCH.

Application filed January 29, 1924. Serial No. 689,221.

To all whom it may concern:

Be it known that I, CHARLES C. SCHREIL, a citizen of the United States, residing at Chicago, in the county of Cook, State of Illinois, have invented certain new and useful Improvements in an Electrical Switch, of which the following is a description, reference being had to the accompanying drawing and to the figures of reference 10 marked thereon.

This invention relates to a switch of the dual or compound type; that is to say, one in which two circuits are controlled by the mechanism contained within a single unitary 15 structure. The switch shown and described herein is particularly adapted for mounting in the end of a steering post on an automotive vehicle. One circuit controlled by the switch may include the horn and the 20 other circuit may preferably be the dimmers for the headlights, or a parking lamp, whichever is desired. While these special uses are mentioned it is, of course, understood that the switch may be used to control 25 other circuits within its range of adaptability.

It is the principal object of my invention, therefore, to provide a compound or dual switch which is simple in construction, easy 30 to manufacture and assemble and one generally efficient in its operation.

My invention will be best understood by reference to the attached drawing in which:

Figure 1 is a sectional view through the 35 complete switch;

Figure 2 is an interior view of the cap as it is removed from the body portion;

Figure 3 is a top view of the body portion which fits with the cap shown in Fig. 2;

Figure 4 is a sectional view on the line 4/4 of Fig. 3;

Figure 5 is a bottom view of the body portion; while

Figure 6 is a complete assembled view of 45 the entire switch.

Referring now to the details, wherein like numbers refer to corresponding parts in the various views, 1 is the body of the switch, preferably made of good insulating material. The body has a centrally located contact 4 having a stem extending through the body to the bottom part, which is preferably cut away slightly as indicated at 17, so that the conductor carried under the head 50 of the screw 12 may be drawn down into the depression and thus securely held in posi-

tion. Carried by the body on either side of the central contact are two contact members 13, screws 14 being used to make connections on their rear end, the same as on the central contact 4. The body 1 has a flange 20 on its upper end and the contacts 13 preferably extend slightly above this flange face for the purpose of making contact with the metallic plate 10 carried by the cap 3. As 60 shown in Fig. 2, this plate is held in position by a screw 11, which is also used to hold a clip 8 in position. The clip 8, as shown in Fig. 1, engages or extends over the flange 20, thereby assisting in holding the 70 body and cap together. However, the cap 3 is adapted to rotate with respect to the body 1, the amount of rotation being limited by the pin 19 which is positioned in a notch 75 cut in the flange 20.

As is indicated in Fig. 1, the flange 20 is adapted to fit within a recess in the bottom of the cap 3 and in one position of the cap, it will be observed the plate 10 is adapted to connect the two contacts 13 together, 80 thereby completing a circuit through these contacts. Fitting within a recess in the upper part of the cap 3 is a push button 2, which has an insert 9 to which is screw threaded a contact member 5, which passes 85 through the cap 3. A spring 6 is used to hold the cap 2 and the contact member 5 in retracted position or so that the parts 4 and 5 do not normally make contact. Movably positioned around the head of the member 5 is a circuit closing member 7, which 90 projects to the exterior of the body 1 and is adapted to lie in the channel 16. This prolongation of the member 7, which lies in the side channel 16, while assisting the clip 8 in holding the body and cap together, 95 it is also used to make contact with the metal part of the steering post, thereby completing a ground connection when the push button 2 is operated.

It will thus be seen that one circuit is controlled by the rotation of the member 3 as heretofore explained, the plate 10 making contact with the members 13 in one position, and when turned to its other position, one of the members 13 moves on to the insulation part 18 (Fig. 2). The other circuit is completed through the contacts 4 and 5 and the member 7.

In assembly, the contacts 4 and 13 are as- 110 sembed in the body 1; the plate 10 and clip 8, together with the push button 2, the con-

fact member 5 and the circuit completing member 7 are assembled to the cap 3; and then the flange 20 of the body 1 is slipped under the clip 8 and pushed forward so that the member 7 slides into the side channel on the body 1, thereby providing a switch which can be taken apart by a slight pull between the body and the cap, no screw drivers or other tools being required.

10 While I have shown one form of my invention, it will be understood that various changes may be made in the details without departing from the spirit of my invention and the scope of the appended claims.

15 Having thus described my invention, what I claim is:

1. In a device of the class described, a body portion having a plurality of contacts, a cap fitting over the body and means for 20 operatively fastening the cap and body together but permitting relative rotation therebetween, a metallic plate carried by the cap and adapted in one position of the cap to connect a pair of said contacts together, a push button movably carried by the cap, a contact member operated by the push button to engage at least one of said plurality of contacts, and a circuit completing member extending from said contact member to the outer periphery of the body.

2. In a device of the class described, a body portion having a plurality of contacts, a cap fitting over the body and means for 35 operatively fastening the cap and body together but permitting relative rotation therebetween, a metallic plate carried by the cap and adapted in one position of the cap to connect a pair of said contacts together, a push button seated within a recess of the cap, a contact member attached to the button and extending through the cap into proximity with at least one of said plurality of contacts, a spring holding 40 the button and contact member in retracted position and a circuit completing member movably engaging said contact member and immovably positioned on the outer periphery of said body.

3. In a device of the class described, a body portion having a flange and a central contact and a contact disposed on both sides thereof, a cap fitting over the body and having a clip for engaging said flange but 55 permitting relative rotation of the body and cap, a metallic plate carried by the cap and adapted in one position of the cap to connect said contacts disposed on the sides of the body, a push button carried by 60 the cap, a contact member operated by the button to engage said central contact in the body, and a circuit completing member movably engaging the contact member but immovably engaging the exterior surface of the body portion.

4. In a device of the class described, a body portion having a channel on the side and a flange at one end, a central contact depressed below the surface of the flange end and a pair of contacts on opposite sides 70 of the central contact and extending slightly above the surface of the flanged end, a cap fitting over the body and having a clip for engaging said flange but permitting relative rotation of the body and cap, 75 a metallic plate carried by the cap and adapted in one position to connect said pair of contacts together, a push button carried by the cap, a contact member adapted to be moved by the cap into engagement with the central contact in the body, and a circuit completing member movably engaging 80 said contact member and extending to and lying in the channel in the body.

5. In a device of the class described, a body portion carrying contacts for two different circuits and extending through the body, said body having a side channel, a cap rotatably attached to the body and having a metallic plate adapted to complete 90 one of said circuits through a pair of said contacts, a push button carried by the cap and carrying a contact member adapted when the button is operated to engage at least one contact in the other circuit, and a circuit closing member movably connected with the push button contact member and extending to and lying in the side channel of the body for the purpose described.

6. In a device of the class described, a body portion carrying contacts for two different circuits and extending through the body, said body having a side channel and a flange, a cap having a recess to receive 100 said flange on the body, a clip carried by the cap for engaging the flange to assist in holding the body and flange together yet permitting rotary movement between the two, a metallic plate carried by the cap for completing a circuit through a pair of said contacts, a push button carried by the cap and carrying a contact member adapted 110 when the button is operated to engage at least one contact in the other circuit, and a circuit closing member movably connected with the push button contact member and extending to and lying in the side channel of the body for the purpose described.

7. In a device of the class described, a body portion carrying contacts for two different circuits and extending through the body, said body having a side channel and a flange, a cap having a recess to receive 120 said flange on the body, a clip carried by the cap for engaging the flange to assist in holding the body and flange together yet permitting rotary movement between the two, a metallic plate carried by the cap for completing a circuit through a pair of said contacts, a pin in the cap and a notch in 130

- the flange to receive said pin to limit the movement of the cap on the body, said cap having a second recess, a push button seated in said second recess, a contact member having a head positioned in the first recess and extending through the cap into engagement with the button, a spring in the second recess holding the button in outward position, said contact member adapted, when the button is pushed, to engage at least one contact in the other circuit, and a circuit closing member movably held under the head of said contact member and extending to and lying in said side channel on the body for the purpose described. 8. In a device of the class described, a compound switch having a body portion carrying contacts for two independent circuits, a cap rotatably mounted on the body and having means for completing one of said circuits through a pair of contacts on the body, a push button carried by the cap and having a contact member adapted to engage at least one contact in the other of said circuits, and a circuit completing member movably connected to the push button contact member and extending to and along the outer surface of the body of the switch as and for the purpose described. 9. In a device of the class described, a body portion having contacts for a plurality of circuits, a cap fitting over the body and means for operatively fastening the cap and body together but permitting relative rotation therebetween, a metallic member carried by the cap and adapted in one position of the cap to complete one of said circuits, a push button movably carried by the cap, a contact member operated by the push button to engage a contact on said body to complete another of said circuits, and a circuit completing member in the last mentioned circuit extending to the outer periphery of said body. 10. In a device of the class described, a body portion carrying contacts for two different circuits and extending through the body, said body having a side channel, a cap rotatably attached to the body and having a metallic member adapted to complete one of said circuits through a pair of said contacts, a push button carried by the cap and carrying a contact member adapted when the button is operated to engage at least one contact in the other circuit and a circuit closing member for the last mentioned circuit extending to and lying in the side channel of the body for the purpose described. 11. In a device of the class described, a compound switch having a body portion carrying contacts for two different circuits, a cap rotatably mounted on the body and having means for completing one of said circuits through at least one contact on the body, a push button carried by the cap and having a contact member adapted to engage at least one contact in the other of said circuits, and a circuit completing member arranged in movable relationship to said cap and having a part extending to and along the outer surface of the body of the switch for completing said push button controlled circuit.

In testimony whereof, I affix my signature. 75

CHARLES C. SCHREIL.
